UNITED STATES PATENT OFFICE.

CHESTER C. COOK, OF McMINTNVILLE, TENNESSEE.

SOUND RECORD.

1,409,674.

Specification of Letters Patent. Patented Mar. 14, 1922.

Application filed June 21, 1919. Serial No. 305,732.

To all whom it may concern:

Be it known that I, CHESTER C. COOK, a citizen of the United States, residing at McMinnville, in the county of Warren and State of Tennessee, have invented certain new and useful Improvements in Sound Records, of which the following is a specification.

The present invention relates to improvements in sound records or disks for phonographs, graphaphones or the like. At the present time there are two distinct types of these disk records in use, one having one surface only grooved for musical reproduction and the other having both sides or surfaces grooved. The advantages of the latter over the former, especially as regards the phases of economy of space and expense, are too well known to need comment upon. The great disadvantage, however, lies in the fact that it is seldom that the purchaser gets his own selection on both sides. In other words, while he may select the record for the reproduction on one side, he is obliged to take the manufacturer's selection on the other. He has, of course, resort to the single surface reproduction type but in doing so he loses the important advantages of the double type which have been referred to above.

The object of this invention is to provide an article of manufacture which will permit the purchaser to obtain a sound record of the double type with the combination of reproductions he desires. This is carried out by making the records, preferably relatively thin and each grooved with the sound reproduction upon one side, these being so supplied to the retailer of the sound records. It should be understood that the term "relatively thin" used above and in the claims is intended to comprehend a disk member which is of such a thinness or thickness as to be impracticable for the ordinary handling incident to actual use. These disks are sufficiently thick, however, to permit the purchaser to try out his selection and when he has made his choice of two such records, the retailer places adhesive upon the backs and sticks the two disks together. This form of connection is not necessarily a permanent one because it may be desired to separate the two records for a subsequent change. At any rate my proposal is to employ a readily fusible adhesive so that separation may be effected if desired.

One method of carrying out the invention may be to provide each disk member substantially one-half the thickness of the ordinary well known record disk now in use so that when the two parts are combined they will equal the thickness of that of the normal record referred to.

It will be apparent that two records or disks connected in this manner possess sufficient strength to withstand the usual handling incident to playing without breakage, effecting a saving in storage space required, and yet afford a combination of selections which the purchaser most desires. This arrangement is especially advantageous where the reproduction is of greater length than would be capable of impression upon a single side of a record, in which case the continuation may be placed upon the disk part which forms the other side of the combination record.

I desire it to be understood that I do not wish to be confined to the idea of connection of the two relatively thin records by means of adhesives, for the invention may be carried out by providing mechanical clamping means for connecting and holding the combination records together.

These features will be more apparent by reference to the drawing hereto appended forming a part of this specification, wherein:

Figure 1 represents two thin record disks of the type I propose to employ for combination purposes and which, as hereinbefore explained, may be connected by an adhesive;

Figure 2 is a plan view of a spring ring which may be utilized instead of cementing the records together;

Figure 3 is a similar view of a modified form of sectional ring; and

Figure 4 is a cross section through the ring, considerably enlarged.

The ring in Figure 2, designated 1, is U-shaped in cross section as shown in Figure 4, and is designed to be sprung open and over the peripheral edges of the two disks and being of spring material the distance between the two sides is, preferably, slightly less than the thickness of the two disks so that they will be effectively gripped and held against each other. It will be apparent that any two disks may thus be arranged in combination and any one changed at will whenever desired.

The form of ring depicted in Figure 3 differs only in that it is provided with hinged

sections 2 and 3, connected at 4, and this merely facilitates the application of the connector device or clamp to the records.

The ring forms rather an attractive than a detracting feature, especially if finished with a highly nickeled or silvered surface. Further, the metal provides a protection not only against the breakage but against scratching of the sound reproducing or 10 grooved surfaces by contact with dust upon the table of the reproducing apparatus or elsewhere.

Having thus described my invention, what I claim as new is:—

15 1. As a new article of manufacture, a sound record comprising two separate complete relatively thin disks, and means engageable with said disks for connecting them back to back in such manner as to be readily separable.

20 2. As a new article of manufacture, a sound record comprising two relatively thin disks each having a sound reproduction upon one side of a predetermined selection, and

yieldable means engageable about the edges 25 of said record disks to connect them back to back to form a combination record.

3. As a new article of manufacture, a combination sound record comprising two relatively thin disks, each having the sound 30 reproduction upon one side only, and a yieldable ring member engageable about the peripheries of the two disks to connect the two disks back to back.

4. As a new article of manufacture, a 35 combination sound record comprising two relatively thin disks each having the sound reproduction upon one side only, and a ring member engageable about the peripheries of the two disks to connect the two disks back 40 to back, said ring being of spring material substantially U-shaped in cross section and the distance between the sides of said ring being slightly less than the thickness of the two disks whereby said disks will be firmly 45 clamped when engaged by the ring.

In testimony whereof I affix my signature.
CHESTER C. COOK.
